UNITED STATES PATENT OFFICE.

JOSEPH H. COSSMAN, OF NEW YORK, N. Y.

MACHINE FOR GRINDING THE EDGES OF LENSES.

1,171,028.

Specification of Letters Patent.

Patented Feb. 8, 1916.

Application filed October 28, 1913. Serial No. 797,715.

To all whom it may concern:

Be it known that I, JOSEPH H. COSSMAN, a citizen of the United States, residing at New York, in the county of New York and 5 State of New York, have invented certain Improvements in Machines for Grinding the Edges of Lenses, of which the following is a specification.

The objects of this invention are to enable 10 a plurality of lens-holding means to be employed with a single grinding stone, each of which means can be operated independent of the others to grind lenses; to provide a series of such means at each end of 15 the grinding-stone frame, at opposite peripheral points of the stone; to provide means for actuating each lens-holding means of such a series from the next preceding one; to secure a compact arrangement, whereby a 20 large number of units can be employed in connection with a grinding stone and all tended by a single operator; to enable the lenses to be readily and quickly inserted and yet with great accuracy, so that they will 25 be ground true and exact; to enable different numbers of lenses to be properly supported in the same carrier; to provide a tension for holding the lenses against the stone which can be readily adjusted; to enable 30 the lens-holding means to be tilted back and held away from the stone without releasing the tension; to discontinue the rotation of the lenses in any one of the lens-holders simultaneously with said tilting 35 back thereof; to provide for a second or further tilting back of each lens-holder, which also simultaneously releases the tension for holding the lenses against the stone; to suitably limit the amount of both such 40 tiltings; to secure improved means for regulating the sizes to which lenses may be ground, and indicating means therefor arranged convenient to the view of the operator; to secure strength and rigidity of 45 construction, with simplicity of operation, and to obtain other advantages and results as may be brought out in the following description.

Referring to the accompanying drawings, 50 in which like numerals of reference indicate the same parts throughout the several views, Figure 1 is a side elevation of a machine for

grinding the edges of lenses embodying my invention; Fig. 2 is a view looking toward the edge of the grinding stone and showing 55 on larger scale one of the lens-supporting means which is viewed endwise in Fig. 1; Fig. 3 is a plan of said lens-supporting means; Fig. 4 is a sectional view taken on a plane through the axes of the swinging 60 carriage and the lens-holder; Fig. 5 is a sectional view taken on line A—A of Fig. 2 looking in the direction of the arrows; Fig. 6 is an end view of a certain tension adjusting sleeve with the key for operating the 65 same; Fig. 7 shows a pattern which may be used in my improved machine to determine the shape of the lenses; Fig. 8 shows in perspective a lever for releasing the lens-carrier members from the lenses; Fig. 9 is a perspective view of a removable head which may be used in different sizes to engage the 70 lenses to be ground; Fig. 10 is a sectional view of a certain gage for determining the size to which the lenses are ground, taken on 75 line B—B of Fig. 3; Fig. 11 is a detail section on line C—C, Fig. 4, illustrating a certain spring catch for holding the swinging carriage tipped back to insert or remove lenses, and Fig. 12 is a perspective view of 80 a bearing bracket for the driving sprocket wheel.

In said drawings, 1 indicates a frame having bearings 2, 2 in which is journaled the shaft 3 of a grinding stone 4, all of which 85 parts may be of any ordinary and well-known construction. It will be understood that such stones are already in use, and upon the upper part of one end of the frame 1 is commonly supported means for grinding 90 upon the stone the edges of lenses, which old means I have not shown in the drawings although a space is provided to receive the same at the left-hand end of the frame in Fig. 1. 95

In carrying out my invention, I mount upon the frame 1 in such position as to leave proper space for the said grinding device heretofore employed, side pieces or stanchions 5, 6 which are firmly secured to the 100 frame 1 and project upward therefrom on opposite sides of the grinding stone to support the various parts next to be described. Preferably, a narrow base plate 7 is se-

cured on top of the side pieces 5, 6, at their ends away from the grinding stone, and has near its ends upwardly projecting bearings 8, 9, one of which, as 8, receives a bushing 10 preferably loose with respect to said bearing, and the other bearing 9 receives a sleeve 11 having outside the bearing a wheel 12 for manually turning it. Within said bushing 10 and sleeve 11 is mounted a main shaft 13, and upon the outside of said bushing and sleeve, as trunnions, is mounted a rocking or swinging carriage 14. This carriage consists of a tubular portion 15 the ends of which receive said trunnions formed by the bushing 10 and sleeve 11, and from which tubular portion 15 project lateral longitudinally alined arms 16, 17 and 18 all of which provide bearings at their upper ends for the rotary lens carrier. Said lens carrier 20 comprises alined end portions or members adapted to clamp the lenses between themselves, one of said members being longitudinally stationary and comprising a rotary spindle 19 mounted in the bearing of the 25 arm 18 with its inner end or end next the other member of the lens carrier receiving a plate 21 against which the lenses 22, each having on opposite sides of itself washers 23, are adapted to be clamped. The outer end of 30 the spindle 19, or end away from the said plate-receiving end, receives a gear-wheel 24 meshing with a gear-wheel 25 on the shaft 13, and the hub of this gear-wheel, in conjunction with a collar 20 on the spindle at 35 the opposite end of its bearing in the arm 18, holds the spindle against longitudinal displacement. The other end portion or member of the lens carrier comprises a longitudinally slidable spindle 26, upon which is 40 mounted a bushing 27 adapted to rotate within the bearings of the arms 16 and 17. Rotary motion is transmitted to the bushing 27 by means of a gear-wheel 28 fast upon the outer end thereof adjacent the bearing 45 provided in the arm 16, said gear-wheel 28 meshing with a gear-wheel 29 fast upon the main shaft 13. It is to be understood that these gear-wheels 28 and 29 should have the same ratio one to the other as do the corresponding gear-wheels 24 and 25 upon the opposite end of the carriage 14, whereby the spindle 19 and the bushing 27 are rotated at the same rate. Furthermore, it may here be noted that it has been found practicable under some circumstances to omit entirely one set of gear-wheels 24 and 25 or 28 and 29 and drive only by means of the other set, so that I do not wish to be restricted to use of the double drive shown.

60 Returning to the lens carrier being described, the bushing 27 is provided at the inner side of the middle arm 17 and its bearing with an enlarged end portion 30 forming a shoulder to prevent movement of the bushing 27 longitudinally outward, and as the gear-wheel 28 is secured onto said bushing adjacent to the relatively opposite side of the bearing in the other arm 16, longitudinal movement of the bushing is thereby prevented inwardly.

70 A collar 31 is fixed upon the bushing 27 adjacent the inner side of the bearing of the outer arm 16, and against this collar bears a helical spring 32 mounted on the bushing. Said spring bears at its other end against a 75 collar 33 surrounding the bushing, the collar being provided with a screw 34 in itself projecting through a longitudinal slot 35 in the bushing and engaging in the spindle 26. By this construction, therefore, the spindle 26 may be longitudinally slid within the bushing by virtue of the slot 35 and yet the screw 34 engaging the sides of the slot transmits any rotary movement of the bushing to the spindle. Furthermore, the interposition of the spring 32 under compression between the collar 31 fixed upon the longitudinally stationary bushing 27 and the collar 33 fixed to the longitudinally slidable spindle 26 normally slides said spindle toward the other member of the lens carrier so as to clamp the lenses 22 against the end thereof. Preferably, the collar 31 has, extending over the spring 32, a cylindrical portion 36 adapted to telescope with a similar sleeve 37 extending toward it from the other collar 33, and spaced from the bushing so as to admit said spring therebetween. The inner end of the spindle 26, just beyond the said bushing 27, is provided with a removable head or tip 38, said head preferably having an enlarged bearing surface faced with some material such as rubber, as shown at 39 in the drawings, to engage the lenses. In order to removably secure the 100 said head 38 to the spindle to rotate therewith, it is screw-threaded on its reduced end 40 and adapted to be screwed into an appropriate threaded hole in the end of the spindle, and to be removed therefrom when the 105 lens carrier sections are separated by sliding the spindle 26 outward as has been mentioned. Heads of different lengths are preferably provided for grinding different numbers of lenses at a time. The tendency of the spring 32 already described is to force said spindle 26 and its head 38 toward the longitudinally stationary spindle 19, whereby lenses are clamped therebetween for grinding, as shown. In order to slide said 110 spindle within its bushing 27 against the action of the spring 32, so as to insert or remove lenses, I provide a lever, shown in Fig. 8 in detail, pivoted as at 41, see Fig. 2, to the middle arm 17 and adapted to engage the collar 33 on the spindle 26 and slide said spindle outward as desired. Said lever comprises a pair of parallel cam plates 42, 42, the cam edges of which are provided with inwardly directed flanges 43, 43 for en-

115 120 125 130 135

gagement against the collar 33 already described on the spindle 26 to slide said spindle. A handle 44 joining the said cam plates 42, 42 above the spindle 26 is arranged so as to rotate said cams about the pivotal points 41, 41, said handle preferably lying flatwise along the lens carrier when the same is rotating and projecting upward when the lever is thrown into releasing position.

In order to swing the carriage toward and from the stone to grind the lenses to elliptic shape, I provide a pattern 45 adapted to be removably supported upon an end 15 extension 46 of the bushing 27. (See Figs. 4 and 7.) Pins 47 projecting longitudinally of said bushing from its enlarged end portion 30 engage in radial slots 48 from the central aperture 49 of the pattern. Said 20 pattern is thus held non-rotatably with respect to the supporting bushing, and in order to secure it firmly against the enlarged end portion 30 of the bushing I screw-thread the end extension 46 of the bushing and provide 25 a clamping nut or ring 50 to screw thereon against the pattern, said nut being shown with a knurled periphery for the convenient manipulation thereof. As the spindle 26 is rotated, it necessarily rotates, 30 the bushing, whereby the pattern revolves, it being noted that the same is arranged perpendicular to the axis of such rotation. It is to be understood, also, that the plate 21 upon the spindle 19 is preferably removable and provided with holes to receive pins 35 projecting from said spindle, whereby said plate, which is elliptical, can be placed in position on said pins with its major axis parallel to the major axis of the pattern 45 40 when held upon its pins 47. By such arrangement the accurate and ready insertion of the lenses in relation to the pattern is facilitated, since they need only be placed in the desired relation to the plate 21 in making up a stack to put into the machine for grinding.

The pattern 45 bears against a gage (see Fig. 10) adjustably supported by the bed plate 7, said gage comprising an upwardly 50 extending arm 51, faced near its top with a plate 52, preferably of high resistance to abrasion, for the pattern to bear against, and having a horizontally disposed base or foot 53 longitudinally slidable within a tubular guideway 54 on the under side of said plate 7 or otherwise suitably supported. This foot 53 it will be understood, lies transversely of the swinging carrier, beneath the same, with its arm 51 reaching upward adjacent to the grinding stone, on the opposite side of the carriage from the operator, and held against tipping sidewise by lying in a recess 55 of the face plate 7 between cheek pieces 56, 56 extending preferably both up and down from said plate, as shown. Said

foot 53 is bored longitudinally as at 57 and interiorly threaded to receive a screw 58 having at the front side of the machine a reduced shank 59 and hand-wheel 60 for turning, see Fig. 10. A collar 61 loose on the reduced shank 59 and held against movement by a screw 62 projecting through the lower wall of the guideway 54, lies between the threaded portion of the screw and a pinion 63 fast on the reduced shank 59, so that the screw is held against longitudinal movement. Thus by turning the screw the foot 53 and its arm 51 will be moved with respect to the base plate 7 and pattern 45 to vary the size to which the lenses are to be ground. The pinion 63 engages a rack 64 arranged to slide in a slot 65 cut in the front of a portion 66 of the base plate 7 which projects forwardly therefrom for its middle portion and extends downward as far as the under wall of the guideway 54 for the foot 53 of the gage, as shown in Figs. 2, 3 and 10, and thus as the gage is adjusted by turning the screw, the said rack 64 is slid. A front plate 67 is secured upon the upright front face of the projecting portion 66 of the base plate 7 to cover the front end of the slideway 54 around the reduced shank 59 and also to inclose the rack 64 in its slideway. This front plate 67 is slotted longitudinally to allow an index finger 68 to project from the rack 64 and upon the upper part of the plate 67 a suitable scale 69 is marked to indicate to the operator the movement of the gage. Thus by looking at said scale 69, the operator may set the gage with respect to the pattern 45 so as to grind lenses to any size, said scale being conveniently observed by him as his fingers turn the wheel 60 of the screw.

Attention is again directed to the fact that the elliptic grinding is due to the pattern 45 engaging against the gage, the entire carriage swinging or oscillating about its axis formed by the bushing 10 and sleeve 11 within the lower tubular portion 15, and in order to press the lenses against the stone, or the pattern against its gage, a helical spring 70 is coiled around the shaft 13 within the lower tubular portion 15 of the carriage 14 and attached at one end to the carriage, as by screws 71, and at its other end to the sleeve 11, as at 72. It will be remembered that the sleeve 11 can be turned by the wheel 12, and the desired degree of tension of spring 70 is thus obtained by rotating the sleeve 11. For conveniently turning this wheel 12 to increase the tension in the spring 70, without endangering the operator's hands by proximity to the gears 24, 25, I provide upon the side piece 5 an upwardly projecting ear 73 adjacent the wheel 12, apertured as at 74 longitudinally parallel to the sleeve 11 for receiving the end of a key rod 75 carrying a gear-wheel 76 which

will mesh with the toothed periphery of the wheel 12 when the key rod is so inserted in the ear 73. A hand wheel 77 at the outer end of said key rod 75 provides suitable means for twisting said gear-wheel 76 and thus turning the wheel 12 on the sleeve. This key may be made non-removable or permanently held by the ear 73 if so desired, but I prefer to have it removable whereby 10 the same key may be used on any one of the lens holding devices.

A spring-actuated pawl 78 pivoted between a bracket 79 and the bearing 9, as at 30, see Figs. 2 and 5, and engaging ratchet teeth 81 on the adjacent face of the wheel 12, normally retains the spring 70 against unwinding, but may be manually operated to release said spring tension entirely when desired for swinging the carriage back into 20 idle position. When it is desired subsequently to re-apply the tension of the spring, the key is inserted and wound upon to create the desired pressure to hold the lenses to the stone and the pattern to its gage. This adjustability of pressure of the lenses against the stone is important in the production of lenses accurately ground, because since various numbers of lenses may be ground at a 25 time, correspondingly varying pressures will 30 be required at different times.

When it is desired to merely insert, remove or otherwise manipulate the lenses in the carrier, it is preferable not to have to release the tension in said spring 70, it taking time to readjust it. For this reason I provide at a convenient place, such as on the under side of the tubular portion 15 of the carriage, see Figs. 4 and 11, a depending pin 82 and arranged transversely of the plate 7, so as to press upward toward said pin 82 a leaf spring 83 projecting outward in front of said plate 7 convenient for manual operation. Said leaf spring is provided with a suitable aperture 84 to receive the depending pin 82 from the carriage and so positioned as to admit the pin when the carriage is swung away from the grinding stone, the resiliency of the leaf spring engaging it automatically. This engagement 35 occurs when the carriage is sufficiently tilted, and retains said carriage in such position against the tension of the helical spring 70 until the leaf spring 83 is depressed out of engagement with the pin 82. If, when 40 the carriage is held in this tilted position from the stone, the leaf spring 83 be depressed and the carriage tilted farther back, a lug 85 projecting radially outward from the tubular portion 15 thereof, see Figs. 2, 3 and 5, engages the free end of the pawl 78 for the tension wheel 12, depressing the same so that its other end is raised out of engagement with the ratchet teeth 81 of said wheel, thereby releasing the tension of the 45 helical spring 70 and allowing the carriage

to remain tilted idly away from the grinding stone, a stop 86 being provided on the tubular portion 15 projecting radially outward therefrom to limit such tilt of said carriage by engagement with the plate 7. 70

The main shaft 13 has fast upon itself, preferably just outside its bearing on the base plate 7, a gear-wheel 87, see Fig. 2, by which said shaft is driven from the main shaft 3 of the grinding stone. Such drive 75 may be any suitable train of gearing, but in the drawings, and especially Figs. 1 to 4 thereof, a chain 88 from the shaft 3 of the grinding stone is shown adapted to transmit rotary motion to a sprocket wheel 89 mounted loose upon the end next adjacent to the grinding stone of a counter-shaft 90 parallel to said grinding stone shaft at the side of the swinging carriage 14 next the grinding stone. This counter-shaft 90 may be supported in any suitable manner upon the side piece or stanchion 5 in transverse relation thereto, but I prefer to employ the supporting means shown herein and next to be described. A plate 91 is secured on top of the side piece 5 so as to project horizontally outward away from the other side piece 6, the side piece 5 being recessed to a depth equal to the thickness of this plate 91 to receive the same and also having a bracket 92 extending beneath the plate 91. Screws 93 then secure the plate firmly in position. Directly above the side piece 5, the plate 91 extends forwardly beneath the base plate 7 to the depending portion 66 thereof at its front edge, and the plate 91 also has an upwardly extending flange 94 parallel to the side plate 5, but at such a distance therefrom as brings it in line with the bearing 8 of the base plate 7, the said flange abutting the edge of said bearing next the grinding stone. The counter-shaft 90 has one of its bearings 95 in this flange 94 and another bearing 96 in alignment therewith to the opposite side of the plate 91, all as clearly shown in Fig. 3. The sprocket wheel 89 on the said counter-shaft 90 is at the side of the bearings 95, 96 just mentioned toward the grinding stone, and to support the end of said counter-shaft 90 between said sprocket and the grinding stone I employ a bracket 97 shown in detail perspective in Fig. 12, which is bolted to the inner side of the side piece or stanchion 5 as shown in Fig. 4. This bracket 97 comprises a foot 98 which is bolted to the side-piece 5 and a horizontal body portion 99 which extends beneath the sprocket wheel 89, and an upright arm 100 at the end of said body portion beyond the sprocket wheel which arm provides at its top bearing 101 for the end of the shaft 90. Furthermore, the body portion 99 has projecting from itself toward the grinding stone a guiding trough 102 which receives the chain 88 for a little distance adjacent to the sprocket wheel and prevents its 100 105 110 115 120 125 130

engagement with the sprocket wheel from being disturbed by the shifting of the grinding stone longitudinally of its axes which shifting is common in this class of machinery and pertains to the grinding stone so that it is not shown herein. A sprocket wheel 103 fast with respect to the sprocket wheel 89 receives a chain 104 to drive the lens supporting means next above by means 5 of its driving sprocket 105. Upon the outer end of the said counter-shaft 90 is a pinion 106 adapted to mesh with a gear-wheel 107 mounted on a stud 108 projecting from the flange 94 of the plate 91 and carrying a pinion 109 fixed to the gear wheel 107, said pinion meshing with a gear-wheel 110 on a second stud 111 on the plate flange 94 and which gear-wheel 110 meshes with a gear-wheel 87 on the main shaft 13 of the carriage. A clutch 112 is provided upon the counter-shaft 90 between its bearings 95 and 96 one member 113 of which is formed on the hub of the sprocket wheel 89 and the other member 114 of which is slidably keyed 20 to the counter-shaft. Thus by throwing this sliding clutch member 114 into and out of engagement, the lens carrier will be rotated or stopped, as desired, it being understood that the sprocket wheel 89 rotates continually. In this way, each lens supporting means can be operated from its sprocket wheel independent of whether the other lens supporting means are being operated by their sprocket wheels and without regard to 30 how many lens supporting means are applied to a single grinding wheel. In order to automatically throw this clutch in and out, I preferably provide a shift arm or lever 115 pivoted to spring horizontally upon a pin 35 116 projecting upwardly from the plate 91, see Fig. 3, and forked at one end to engage between collars 117, 117 on the clutch member 114. The other end of this shift arm or lever 115 projects under the swinging carriage 14, where it is provided with a transversely oblique or inclined slot 118 which receives a pin 119 depending from the under side of the carriage, through a slot 120 in the base plate 7 at right angles to the length 40 thereof. Preferably extensions 121, 121 are formed at the ends of the oblique slot 118 in the lever 115, longitudinally thereof, to allow for any further travel of the pin 119 after the clutch has been operated. As the 45 carriage is swung or tilted away from the grinding stone, the pin 119 travels in the lever slot and striking the oblique portion 118 thereof swings the lever sidewise and shifts the slidable clutch member 114 out of engagement with the other member 113.

It will be understood that the position of the oblique slot 118 is such that when the swinging carriage is tilted away from the grinding stone to its first position, that is 50 with the pin 77 in the hole of the spring 78 and the tension spring 66 in full force, the clutch member 114 will be thrown out, and that as the swinging carriage is returned to operative grinding position by releasing the spring 78, the said clutch will be again thrown in. In this way, therefore, as the carriage is tilted away from the stone so as to no longer grind the lenses, the rotation of the lens carrier is automatically discontinued, and tilting the carriage toward the stone again simultaneously starts the lens carrier to rotate. Obviously, the slot 120 in the base plate 7 guides the end of the pin 119 and supports it against any lateral bending or deflection as it presses against the lever 55 115 to swing the same.

The lens supporting means which I have described is shown elevated above the frame 1 of the grinding machine, by the side pieces or stanchions 5, 6, so that it will not interfere with the old forms of supporting means now upon grinding machines, but will lie above the same. When so desired these side pieces 5, 6 may be surmounted by a second pair of side pieces 122 carrying a lens-supporting means 123 similar to the one above described and positioned immediately above the same, see Fig. 1. This second lens-supporting means is preferably driven by the chain 104 from the sprocket 103 on the counter-shaft 90 of the first or next lower lens-supporting means, preferably next adjacent to the driving sprocket 89, as already described, whereby economy of space on the axle 3 of the grinding stone is effected by 60 necessitating only the one drive therefrom to operate the series of lens-supporting means. It will be understood that still another or third lens-supporting means 124 may be applied over the others, see Fig. 1, 65 and indeed the number of lens-supporting means in the series is limited only by the size of the grinding stone or demands of the user.

It is to be noted that as herein used the term "lens supporting means" is that portion of the device other than the side pieces 5, 6 and the driving means, said driving means including the train of gears from the gear wheel 87 on the shaft 13 to the pinion 106, together with the counter shaft 90, the clutch 112 with its shifting lever 115 and the driving sprockets and chains. It is to be understood, however, that in superposing the lens supporting means one above the other, suitable side pieces and driving means are provided for each of said lens-supporting means. In operation, the several sprocket wheels are run continuously, but the lens supporting means is only operated 70 when desired, so that one of said supporting means may be operating to grind lenses while another one is being attended by the operator, and so forth.

Preferably the engaging edges of the side 75 130

pieces or stanchions of the different lens-supporting means are disposed in lines which pass through the axle 3 of the grinding stone, as shown particularly in Fig. 1, 5 this arrangement resulting in the same disposition of the various parts of the different lens-supporting means with reference to the peripheral surface of the grinding stone. Furthermore, I prefer to mount upon the 10 opposite end of the frame 1 of the grinding stone, a second series of lens-supporting means extending upward therefrom as indicated in Fig. 1. This series might be exactly like the series which has been already described, but since it has not been customary 15 in practice to employ more than one lens-supporting means with a grinding stone, it is usually unnecessary to provide at the second end of the grinding stone space for a 20 lens-supporting means already in use, as I have shown and described at the first end of the frame. I therefore have shown one of my improved lens-supporting means, as 125, with supporting side pieces or stanchions 25 126 which are low and merely strips secured to the frame 1. Then by side pieces 127, extending up from these strips 126, I support a next higher lens-supporting means 128, and above that another one 129 supported by 30 side pieces 130. In this way, a series of lens-supporting means may be provided at this end of the grinding machine, their construction and operation being similar to that described in connection with those at the front 35 end of the machine. The series at this second end of the machine may, like the first, be extended upward as far as desired, and thus a large number of lens-supporting means secured in connection with a single 40 grinding stone. Because of the compact arrangement of all the lens-supporting means upon the one grinding machine or stone, it is easy for a single operator to tend them all and much space as well as cost of installation is saved. While the operator is removing or arranging the lenses in one of the 45 supporting means, the lenses in others of said supporting-means may be grinding, it being thus made possible to grind a large 50 number of lenses at one time. Moreover, since each lens-supporting means of my improved machine can be set or adjusted independent of the rest, a plurality of lots of lenses of different shapes or sizes can be 55 ground at the same time, and on the same grinding stone. Also since there is a series of lens-supporting means, by my invention, different ones may be kept set to grind different standard sizes or shapes of lenses and 60 thus the machine is always ready to grind any of those sizes or shapes without adjustment.

Having thus described the invention, what I claim is.

65 1. In a machine of the character described,

the combination with a grinding stone, of lens supporting means adapted to present lenses to said grinding stone, a second lens supporting means mounted upon the first-mentioned lens supporting means and adapted to present lenses to a different portion of the periphery of said grinding stone at substantially the same angle thereto as said first-mentioned lens supporting means presents its lenses, driving connections for operating the first-mentioned lens supporting means from the grinding stone, and other driving connections for operating the said second lens supporting means from said first-mentioned driving connections. 70 75 80

2. In a machine of the character described, the combination with a grinding stone, of lens supporting means adapted to present lenses to said grinding stone, a second lens supporting means mounted upon the first-mentioned lens supporting means and adapted to present lenses to a different portion of the periphery of said grinding stone at substantially the same angle, driving connections for operating the first-mentioned lens supporting means from the grinding stone, other driving connections for operating the said second lens supporting means from said first-mentioned driving connections, and a clutch in one of said driving connections at 90 a point farther away from the grinding stone than the union of the two driving connections. 95

3. In a machine of the character described, the combination with a substantially horizontal elongated frame and a grinding stone mounted therein, side pieces mounted at one end of said frame on opposite sides of said grinding stones in planes substantially parallel therewith, the top and bottom edges of each of said side pieces being inclined to each other, a second pair of side pieces upon said first mentioned side pieces having their top and bottom edges inclined to each other, and lens supporting means between corresponding pairs of side pieces adapted to present lenses to the periphery of said grinding stone. 100 105 110

4. In a machine of the character described, the combination with a frame and a grinding stone having an axle mounted in said frame, of side pieces mounted on said frame on opposite sides of said grinding stone, a shaft carried by said side pieces substantially parallel to said axle, a carriage mounted to swing on said shaft providing a rotary lens carrier adapted to be rotated by said shaft and present lenses to the grinding stone, a counter shaft mounted on one of said side pieces substantially parallel to said axle and carriage shaft between the two, means for driving said carriage shaft from the counter shaft, a sprocket rotatably loose on said counter shaft, means for driving the sprocket from the axle, and clutch means for 115 120 125 130

- connecting said sprocket and counter shaft as desired.
5. In a machine of the character described, the combination with a frame and a grinding stone having an axle for mounting said grinding stone in said frame, of a lens supporting means, a sprocket wheel therefor, a sprocket wheel on said axle, a chain connecting said sprockets, and a guiding trough for 10 said chain for preventing dislodgment of said chain from its sprockets.
6. In a machine of the character described, a lens supporting means comprising a base, a swinging carriage mounted on said base, a lens carrier journaled in said carriage, a 15 helical spring arranged longitudinally of the line of hinging of said carriage adapted when tightened to swing the carriage in one direction, and means for automatically releasing said spring by swinging the carriage in the other direction.
7. In a machine of the character described, a lens supporting means comprising a base, a swinging carriage mounted on said base, a lens carrier journaled in said carriage, a 20 helical spring arranged longitudinally of the line of hinging of said carriage, means for tightening said spring, and a detent for said tightening means adapted to be released by 25 engagement of the carriage when swung.
8. In a machine of the character described, a lens supporting means comprising a base, a swinging carriage mounted on said base, a lens carrier journaled in said carriage, a 30 helical spring arranged longitudinally of the line of hinging of said carriage, a ratchet wheel for tightening said spring, and a spring controlled pawl normally engaging said ratchet wheel and adapted to be released by 35 the carriage when swung.
9. In a machine of the character described, the combination with a swinging carriage providing alined bearings, of a member rotatably mounted in one of said 40 bearings, a longitudinally stationary bushing in alinement with said member adapted to rotate, gear wheels fast upon the outer ends of the member and bushing, a shaft for driving said gear wheels in unison, a 45 pattern on the inner end of said bushing, a spindle slidably mounted in said bushing adapted to clamp lenses between itself and said member, and means for preventing angular displacement between said spindle 50 and bushing.
10. In a machine of the character described, the combination with a swinging carriage providing alined bearings, of a member rotatably mounted in one of said 55 bearings, a longitudinally stationary bushing in alinement with said member adapted to rotate, gear wheels fast upon the outer ends of the member and bushing, a shaft for driving said gear wheels in unison, a pattern on the inner end of said bushing, a 60 spindle slidably mounted in said bushing, a collar slidably mounted on said bushing, means connecting said spindle and collar to slide together and prevent rotation thereof with respect to the bushing, and a spring on 65 said bushing normally pressing the collar and spindle toward said member.
11. In a machine of the character described, the combination with a swinging carriage providing alined bearings, of a member rotatably mounted in one of said 70 bearings, a longitudinally stationary bushing in alinement with said member adapted to rotate, gear wheels fast upon the outer ends of the member and bushing, a shaft for driving said gear wheels in unison, a pattern on the inner end of said bushing, a spindle slidably mounted in said bushing, a 75 collar slidably mounted on said bushing, means connecting said spindle and collar to slide together and prevent rotation thereof with respect to the bushing, and a spring on 80 said bushing normally pressing the collar and spindle toward said member.
12. In a machine of the character described, a lens supporting means comprising a base, a swinging carriage mounted on said base adapted to be swung toward the grinding stone in operative position or swung away from said stone into idle position or tilted partially between its operative 85 and idle position into a middle position, and means for stopping and holding said swinging carriage in its middle position when swung thereto from either of its other positions.
13. In a machine of the character described, a lens supporting means comprising a base, a swinging carriage mounted on said base, a lens carrier journaled in said carriage and having a pin projecting toward the base, and a leaf spring mounted on said base normally engaging said carriage and having an aperture adapted to receive said pin.
14. In a machine of the character described, a lens supporting means comprising a base, a swinging carriage mounted on said base, and having a radially projecting pin depending therefrom, a lens carrier journaled in said carriage, means for rotating 100 said lens carrier including a clutch, and a clutch lever fulcrumed in fixed relation to said base and having an end projecting between said base and carriage and having a slot inclined to the plane of rotation of the 105 pin and receiving said pin so as to swing the lever by swinging the carriage.
15. In a machine of the character described, a lens supporting means comprising a base having a slot therein, a swinging 110

carriage mounted on said base and having a pin depending therefrom and projecting into said slot, a lens carrier journaled in said carriage, means for rotating said lens carrier including a clutch, and a clutch lever fulcrumed with its end projecting between said base and carriage and having a slot in-

clined to the plane of rotation of the pin and receiving said pin so as to swing the lever by swinging the carriage.
